CLAIM

The ornamental design for a guide for carrying out word games, as shown and described.

[21] Appl. No.: 379,893

DESCRIPTION

FIG. 1 is a perspective view of a guide for carrying out word games, showing my new design;

FIG. 2 is a top plan view thereof;

FIG. 3 is a front elevational view thereof;

FIG. 4 is a bottom plan view thereof;

FIG. 5 is a rear elevational view thereof; and,

FIG. 6 is a left side elevational view thereof, the right side being a mirror image.
